Edward G. Knowles INVENTOR

BY

Thomas Howe ATTORNEY

UNITED STATES PATENT OFFICE.

EDWARD G. KNOWLES, OF NEW YORK, N. Y.

GAME

Application filed April 14, 1923. Serial No. 631,961.

To all whom it may concern:

Be it known that I, EDWARD G. KNOWLES, a citizen of the United States, residing at city, county, and State of New York, have 5 invented new and useful Improvements in Games, of which the following is a specification.

This invention relates to shooting games wherein are employed objects to be struck 10 by a projectile or missile thrown or shot by an instrument as, for instance, a cork projected by the usual pop-gun.

The main object of the present invention is to provide a practical and realistic target 15 device whereby the game is rendered attractive and the interest in it is enhanced.

A further object of the invention is to provide a game of the character indicated which shall be simple in construction, easy 20 to set up and operate.

A further object of the invention is to provide a game of the class described which shall, while giving an extensive view or scene, be capable of folding or collapsing 25 into compact proportions.

Other and ancillary objects of the invention will appear hereinafter.

In the accompanying drawings which illustrate the invention:—

30 Fig. 1 is a perspective view, from the front, of the apparatus in operative position;

Fig. 2 is a top plan view of the apparatus as shown in Fig. 1;

Fig. 3 is a section on the line 3—3 of 35 Fig. 2;

Fig. 4 is a fragmentary view showing, in enlarged perspective, a means for mounting objects upon the scenery; and

Fig. 5 is a perspective view of one of the 40 members representing an animate object.

Referring to the drawings, the box 1 has hinged thereto the lid 2 in any suitable manner. Extending upwardly from the bottom of the box are representations 3 and 4 of 45 rocks which are hinged to the bottom of the box so that they may be folded down when it is desired to close up the game and put it away. Also hinged to the bottom of the box are the flat plate-like scenic members 5 and

50 6, the front surfaces of which are in substantially the same planes respectively, and upon these front surfaces are painted the desired scenes. These plates, it will be seen, when in raised position as shown in Fig. 1, 55 are expanded far beyond the confines of the

box in a vertical direction and these members also comprise the parts 7 and 8 respectively which are hinged to the other portions of the scenic members so that they may be swung outwardly to extend laterally beyond 60 the confines of the box as shown in Fig. 1, or may be folded inwardly on their hinges so as to come within the confines of the box when it is closed. These scenic members may be arranged one back of the other as 65 shown, to produce the desired effects and further scenes, as shown in Fig. 1, may be painted upon the inside of the lid. The scenic members are held in upright positions 70 by means of struts as 9 hinged to their backs so that they may be folded up flat against the scenic members and to these struts are secured strings 10, the other ends of which are secured to the lid so that as the lid is opened the struts will be extended and the 75 scenic members drawn into upright position.

Extending from the lid is a hanger hook 11 from which is swung the representation of a bird 12 holding its prey. The hook 11 may be hinged to swing laterally in closing 80 the box or it may be made so short that it will not interfere with the closing of the lid.

Hinged to the back of the scenic member 5 are shelves 13 and 14, these shelves being 85 adapted to be held in extended position by the flaps 15' and 16' hinged to the ends of the shelves. This hinging permits of the collapsing of the shelves flatly against the scenic member in packing the device in the box. Standing upon these shelves respec-

90 tively are the members representing the bear 15 and tiger 16, while mounted upon the member 6 by means of the spring 17 is the object 18 representative of a lion, all of these 95 animals being in the attitude of approaching their prey beneath them, namely the deer 19 standing upon the bottom of the box. The bear 15, tiger 16 and the deer 19 are not fixed to their supports but merely rest upon them so that when a missile strikes the bear 100 or tiger it is knocked off the shelf and also they may be conveniently placed in packing.

Also the lion is movably mounted by means of the spring so that when struck by a missile this is indicated by its movement, 105 but it resumes its original position and does not require to be replaced by hand.

Also the eagle 12 when struck by a missile 110 swings to indicate that fact, but resumes its normal position automatically.

At the front of the box a compartment is formed by means of the partition 20 within which may be placed a pop-gun 21 and a supply of corks 22.

5 Supported at the front of the lid is a net of mosquito netting 23 or other suitable material which will catch the shot corks with a cushioning impact so that the corks will fall almost directly downward instead of 10 bouncing about the room and also the noise of impact will be reduced.

All of the articles being folded within the box and the lid being closed down tight, as will be the proper condition of the game 15 when not in use, if it be desired to place the game in operation the lid is raised thereby drawing the members 5 and 6 into upright position and the parts 7 and 8 are swung laterally outward. The animals 15 20 and 16 are then placed in position on their respective shelves and the deer is placed in suitable position. The gun and corks having been taken out the game is played by endeavoring to hit the lion, bear, tiger or 25 eagle with a projected cork. If either of the animals 15 or 16 is struck this will be indicated by its being knocked off the shelf as it is not secured thereto. The striking of the eagle will result in its swinging while 30 the lion will move backwardly on its spring when struck and will, after some vibration, resume its normal position.

When it is no longer desired to use the game, the gun and corks may be placed in 35 the compartment as referred to, the parts 7 and 8 may be folded inwardly against the main portions of the scenic members 5 and 6, the members 3 and 4 are folded down against the bottom of the box, the loose 40 animals, such as 15, 16 and 19 may be laid down flatwise upon the bottom of the box, the hanger hook 11 may be folded against the top of the lid and then when the lid is closed down the members 5 and 6 will 45 fold down or collapse into the box. The box then being closed, the device may be put away in compact form.

While the invention has been illustrated in what is considered its best application 50 it may have other embodiments without departing from its spirit and is not therefore limited to the structures shown in the drawings.

What I claim is:

55 1. In a shooting game, the combination with a box having a lid, of scenic members and members representing animate objects, said members being mounted on said box and said scenic members having certain 60 dimensions greater than certain dimensions of said box whereby they are adapted, when said lid is opened, to be expanded beyond the confines of the box, said objects being exposed so as to be struck by a projectile from the front of the game, and said scenic mem-

bers having other dimensions less than certain dimensions of said box whereby they are adapted to be collapsed within said box and lid when closed.

2. In a shooting game, the combination 70 with a box having a lid, of scenic members and members representing animate objects, said members being mounted on said box, said scenic members having certain dimensions greater than certain dimensions of 75 said box whereby they are adapted when said lid is opened to be expanded beyond the confines of said box, said objects being mounted on said scenic members when they are in expanded position so as to be exposed to be struck by a projectile from the front, said scenic members having other dimensions less than certain dimensions of said box whereby they are adapted to be collapsed within said box and lid when closed. 85

3. In a shooting game, the combination 90 with a box having a lid, of scenic members and a member representing an animate object, said members being mounted on said box, said scenic members having certain dimensions greater than certain dimensions of said box whereby they are adapted when said lid is opened to be expanded beyond the confines of said box, said object being spring 95 mounted on one of said scenic members when they are in expanded position so as to be exposed to be struck by a projectile from the front, said scenic members having other dimensions less than certain dimensions of said box whereby they are adapted to be collapsed within said box and lid when closed. 100

4. In a shooting game, the combination 105 with a box having a lid, of scenic members and members representing animate objects, said members being mounted on said box and said scenic members having certain dimensions greater than certain dimensions of said box whereby they are adapted, when said lid is opened, to be expanded both vertically and laterally beyond the confines of the box, said objects being exposed so as to be struck by a projectile from the front of the game, and said scenic bodies having other dimensions less than certain dimensions of said box whereby they are adapted to be collapsed within said box and lid when closed. 110

5. In a shooting game, the combination 115 with a box having a lid, of scenic members and members representing animate objects, said members being mounted on said box, said scenic members being hinged to said box and having certain dimensions greater than certain dimensions of said box whereby they are adapted, when said lid is opened, to be expanded beyond the confines of the box and said objects being exposed so as to be struck by a projectile from the front of the game, and said scenic members having 120

125

130

other dimensions less than certain dimensions of said box whereby they are adapted to be collapsed within said box and lid when closed.

- 5 6. In a shooting game the combination with a box having a lid, of scenic members and members representing animate objects mounted on said box, said objects being mounted in position so as to be exposed to be struck by projectiles from the front and said lid forming a backstop for projectiles aimed at said objects, and means for cushioning the impact of the projectiles.
- 10 7. In a shooting game the combination with a box having a lid, of scenic members and members representing animate objects mounted on said box, said objects being mounted in position so as to be exposed to be struck by projectiles from the front and

- 15 20 said lid forming a backstop for projectiles aimed at said objects, and a netting in front of said lid for cushioning the impact of the projectiles.

- 25 8. In a shooting game the combination with a box having a lid, of scenic members and members representing animate objects exposed so as to be struck by projectiles from the front, said members having certain dimensions greater and certain other dimensions less than certain dimensions of said box whereby they are adapted to be collapsed within the box and lid when closed and to be expanded beyond the confines of the box when the lid is opened, and operative means whereby the movement of the lid in opening operates to move said members into expanded position.

- 30 35 40 9. In a shooting game the combination with a box having a lid of scenic members mounted upon the box and a member representing an animate object suspended in swinging relation to said lid and exposed

so as to be struck by a missile from the front.

10. In a shooting game the combination with a box having a lid, of substantially flat scenic members having the scenery depicted thereon on substantially plane surfaces, said flat members being hinged to said box and adapted to be folded therein or raised into operative position as desired.

11. In a shooting game the combination with a box having a lid, of substantially flat scenic members having the scenery depicted thereon on substantially plane surfaces, said flat members being hinged to said box and adapted to be folded therein or raised into operative position as desired, and members representing animate objects mounted upon said scenic members.

12. In a shooting game the combination with a box having a lid, of substantially flat scenic members having the scenery depicted thereon on substantially plane surfaces, said flat members being hinged to said box and adapted to be folded therein or raised into operative position as desired, and means for operating said scenic members by the movement of said lid.

13. In a shooting game the combination with a box having a lid, of substantially flat scenic members having the scenery depicted thereon on substantially plane surfaces, said flat members being hinged to said box and adapted to be folded therein or raised into operative position as desired, and members representing animate objects mounted upon said scenic members, and means for operating said scenic members by the movement of said lid.

In testimony whereof I have signed this specification this 11th day of April 1923.

EDWARD G. KNOWLES.
